UNITED STATES PATENT OFFICE.

ROBERT J. JOHNSON, OF SHERIDAN, WYOMING, ASSIGNOR TO SHERIDAN IRON WORKS,
OF SHERIDAN, WYOMING, A CORPORATION OF WYOMING.

FLUME.

1,073,857.

Specification of Letters Patent. Patented Sept. 23, 1913.

Application filed July 16, 1912. Serial No. 709,769.

To all whom it may concern:

Be it known that I, ROBERT J. JOHNSON, a citizen of the United States, residing at Sheridan, in the county of Sheridan and 5 State of Wyoming, have invented a new and useful Improvement in Flumes, of which the following is a specification.

My invention relates to certain new and useful improvements in flumes and is de- 10 signed more particularly for irrigation purposes where but slight pressure is re- quired, and is fully described and explained in the specification and shown in the accompanying drawings, in which:-

15 Figure 1 is a cross-sectional view and Fig. 2 a section on the line 2 of Fig. 1.

As shown my improved flume structure consists of overlapping members, one of the 20 end-joints of each of which is provided with a square outward projection 14 of a bead- like character and the other has a similar projection 15, but of a sufficiently smaller size to fit within the projection 14, as shown in Fig. 2. An outwardly-facing channeled 25 member 16 is placed within the latter depression so as to give a smooth inner surface to the flume. In this way a very rigid and strong joint between adjacent sections of the flume is provided. The flume is readily 30 supported in position on the posts 16¹ illustrated diagrammatically in Fig. 1 by brackets 17, which are secured to the top of the posts and are connected by a truss-rod 18 drawn around under the flume and lying in a 35 groove 19 in the outward bead-like projec- tion 14. This flume construction, it will be

seen, is composed of sections which can be nested.

I am aware that considerable variation is possible in the details of construction herein 40 shown and described, without departing from the spirit of my invention, and I do not intend to limit myself thereto, except as pointed out in the following claim, in which it is my intention to claim all the novelty 45 inherent in the structure shown and described as broadly as the state of the art will permit.

What I claim as new and desire to secure by Letters Patent is:

A flume open from end to end and composed of metal sections having their meeting ends formed with projections adapted to fit one within the other, an outwardly fac- 50 ing channel-member adapted to be placed 55 within the inner projection to give a smooth inner surface to the flume, vertical posts op- 55 posite the meeting ends of the sections, brackets connected to the upper end of said posts, having flanges extending over the sec- 60 tions, and a truss rod extending beneath the meeting ends of said sections and having its 65 ends extending through the said brackets, and securing and tensioning means on the ends of said rods.

In testimony whereof I have hereunto set my hand this 1st day of July, 1912.

ROBERT J. JOHNSON.

In presence of two subscribing witnesses:

H. N. GOTTLIEB,

FRED H. BLUME.
